UNITED STATES PATENT OFFICE

ANNE M. BOEVER, OF HARTFORD, CONNECTICUT, ASSIGNOR TO THE SILEX COMPANY,
A CORPORATION OF CONNECTICUT

DESIGN FOR A HEATER STAND FOR COFFEE MAKERS

Application filed August 13, 1929. Serial No. 32,401. Term of patent 14 years.

To all whom it may concern:

Be it known that I, ANNE M. BOEVER, a citizen of the United States, residing at Hartford, in the county of Hartford and State of Connecticut, have invented a certain new, original, and ornamental Design for Heater Stands for Coffee Makers, of which the following is a specification, reference being had to the accompanying drawings, forming part thereof.

In these drawings,—

Figure 1 is a side elevation of the article showing my new design, and

Fig. 2 is a plan view of the same.

I claim:

The ornamental design for a heater stand for coffee makers, substantially as shown.

In testimony whereof I affix my signature.

ANNE M. BOEVER.
